(57) **CLAIM**

The ornamental design for a combined ceiling fan motor housing, blade holders and light unit, as shown and described.

DESCRIPTION

FIG. 1 is a perspective view of a combined ceiling fan having a motor housing, blade holders and a light unit, and plurality of blade holders constructed in accordance with the present invention, the ceiling fan providing an environment for said motor housing, light unit, and blade holders;

FIG. 2 is an enlarged perspective view of the motor housing, light unit, and blade holders in accordance with the present invention;

FIG. 3 is a slightly enlarged bottom view of the motor housing, light unit, and blade holders in accordance with the present invention; and,

FIG. 4 is a slightly enlarged side view of the motor housing, light unit, and blade holders in accordance with the present invention.

The broken line showing of a ceiling fan canopy, support pole and blades is included for the purpose of illustrating environmental structure and forms no part of the claimed design.
